CLAIM

The ornamental design for a light for a vehicle, as shown and described.

DESCRIPTION

FIG. 1 is an isometric perspective view of a light for a vehicle in accordance with my design;

FIG. 2 is a front elevation thereof;

FIG. 3 is a rear elevation thereof;

FIG. 4 is a top plan view thereof;

FIG. 5 is a bottom plan view thereof;

FIG. 6 is a left side elevation thereof; and,

FIG. 7 is a right side elevation thereof.

The broken lines illustrate portions of the light for a vehicle which form no part of the claimed design.
